A. J. VANCE

COLLAPSIBLE BOX

Filed April 24, 1926

UNITED STATES PATENT OFFICE.

ALBERT J. VANCE, OF CHICAGO, ILLINOIS.

COLLAPSIBLE BOX.

Application filed April 24, 1926. Serial No. 104,277.

This invention relates in general to receptacles, more particularly to paper receptacles, and in the present instance specifically to an improved collapsible box, made of 5 fibre board, card board or other suitable material which will facilitate its use as a shipping and storing case.

This invention finds special utility as a shipping case for clothing and the like and, 10 in general, is found useful in mailing articles of various kinds wherein it is not practicable to ship the articles in a sealed container, such, for instance, in connection with the parcel post laws which forbid the sealing 15 of certain packages, the present invention affording a box which may be effectively closed against opening without breaking the box or a seal, where the same is sealed, and wherein the box, if shipped unsealed, may 20 be readily opened for inspection by the postal authorities.

The principal objects and advantages of the present invention reside in the provision of an improved collapsible shipping receptacle; the provision of an improved collapsible shipping receptacle formed of a single blank of material; the provision of an improved shipping receptacle formed of a single blank of readily scored and folded 30 material such as fibre board or the like; the provision of an improved collapsible receptacle which is of such nature as to reduce the cost of manufacture of such receptacle to a material degree resulting in a saving 35 of material both of the stock itself, the labor involved in constructing and assembling the box and a saving of other material such as stitching and the like.

This invention is further characterized by 40 the provision of an improved corner and side and end walls which serves a dual purpose of retaining certain elements of the box in predetermined relationship and for acting on certain other elements of the box 45 to bring them into a predetermined relationship to facilitate closing of the box; the provision of a box of the character described which may be shipped to the purchaser in substantially flat form so as to save 50 space in shipping large quantities; the provision of a box of the character described which is complete both as to the body and to the cover in one piece and completely assembled for use by the purchaser; the 55 provision of a box of the character described in which the members are all preferably

connected together so that no assembly of the parts of the box by the purchaser is necessary when it is desired to use the same and so that such parts will not become detached, thus permitting the box to be used 60 a number of times if desired.

The foregoing and such other objects and advantages as may appear or be pointed out as this description proceeds are attained 65 in the structural embodiment of the invention illustrated in the accompanying drawing, in which:

Figure 1 is a composite view of a box 70 constructed in accordance with the present invention and illustrating in certain respects alternative features; Figure 2 is a perspective view of a box constructed in accordance with the present invention showing the 75 box partly open and Figure 3 is a transverse sectional view showing the box closed.

The receptacle of the present invention preferably includes an upper and lower section, said section being interfitting when the box is assembled and set up so that the 80 sections form, respectively, a bottom and a closing top.

Referring more particularly to the drawings, and first to Figure 1, for certain purposes I provide a blank of material such as 85 fibre board, card board or the like of a suitable desired gauge, this blank of material being generally designated 10. The blank 10 is suitably scored along the lines 11, 12, 13 and 14 to provide a main portion 16 90 which, for convenience, will be termed the bottom of the box, the scorings 11, 12 and 13 being disposed from the adjacent edges of the blank a sufficient distance to afford an outer side wall 17 and opposite end walls 95 18 and 19.

Adjacent to the bottom 16 but, of course, in spaced relation thereto, the blank 10 is further scored along the lines 11^a, 12^a, 13^a and 14^a to provide the substantially rectangular top portion 20. The scorings 11^a, 12^a, 13^a and 14^a are spaced sufficient distances from the adjacent edges of the blank to afford an outer side wall 21 and opposite end walls 22 and 23 which latter are substantially complementary to the outer side wall 17 and end walls 18 and 19 respectively. 100

The lines of scorings 14 and 14^a are spaced a sufficient distance, preferably according to the side walls 17 and 21, to afford a common side wall 24 for the two sections of the box, this side wall likewise forming a 110

hinge. In order to bring the walls 17 and 18 and 17 and 19 into perpendicular relation and to secure them so as to cause the end walls to be moved into perpendicular relation with the bottom 16, notches 25 and 26 are cut in the blank 10, thus affording diagonally cut tongues 27 and 28 which, by means of the scorings 29 and 30, respectively, are bent to lie along the end walls 18 and 19 bent to lie along the end walls 18 and 19 as best shown in Figure 2. When this is done, suitable stitches 31, 31 are passed through the diagonally cut members 27 and 28 and their respective end walls for fixedly attaching the walls 18 and 19 to the outer side wall 17. In order that the walls 17, 18 and 19 may lie flat on the bottom 16 when packing the receptacles for shipment to a purchaser, the end walls are scored diagonally as at 32 and 33 in such manner as to permit the outer side wall and end walls to fold down upon the bottom 16 or, if desired, to allow the end walls 18 and 19 to lie outwardly and the wall 17 inwardly. In either event, depending on how the walls 18 and 19 are scored, it will be obvious that by swinging up both of the end walls 18 and 19, the side wall 17 will also be caused to swing up into perpendicular relationship with the walls 18 and 19 and with said base 16. The top or closure section of the box is constructed at its outer corners substantially identically with the bottom of the box as shown in Figure 1, and a detailed description need not be included here. It is sufficient to point out that corresponding notches 25^a, 26^a, diagonally cut tongues 27^a and 28^a, and suitable scorings 32^a and 33^a are provided for this purpose.

In order to interlock the walls 19 and prevent access to the box and at the same time maintain these walls in a predetermined position, and, as well, to bring the walls 22 and 23 into predetermined relation to the top section 20, the blank is provided with notches 35 and 36 of such nature as to form termini for the inner ends of the end walls 18 and 19 indicated as at 37 and 38. The notches 35 may be merely slits from the outer edge of the blank and terminating at the scorings 11 and 11^a and 13 and 13^a but for convenience in assembling the box it will be observed that the notches 35 and 36 are shaped to provide connecting portions 39 and 40 with the outer edges thereof slightly inclined so that when these portions 39 and 40 are folded in assembling or setting up, the free edges thereof will not abut the bottom 16 and interfere with proper assembly. The portions 39 and 40 are diagonally scored, as indicated at 41, 41, and further scored as indicated at 42, 42 and 43, 43, so that substantially rectangular scored connecting portions are afforded at this point. It will also be observed from an inspection of Figure 2 that the members 39 and 40 thus, when

folded, form gussets. When the outer side and end walls of each of the sections are respectively joined, I prefer to connect the inner halves of the connecting members 39 and 40 to the common side wall 24 by the provision of stitching 44, 44, as shown in Figure 2, though I have found that this is not absolutely necessary to the proper functioning of the connecting members. It is preferable as it keeps the inner portion of each of the connecting members flat against the common side wall and thus prevents them projecting into the box and interfering with the contents.

The connection of the inner portions of the connecting members 39 and 40 to the common side wall also causes the end walls to be elevated into perpendicular relation with the top 20 when the box is set up and in addition serves to form recesses, as shown in Figure 2, for receiving and retaining the ends 45, 45 and reinforcing strip 46. If this strip is made of a relatively heavy gauge, no gluing will be found necessary, the strip merely being retained by the connecting members 39 and 40. In lighter stock it may be desirable to paste the strip 46 only at its medial portion to the common side wall, as indicated at 47 which will, of course, effectively prevent displacement of the reinforcing strip.

From the foregoing it will be observed that the box, when the end and side walls of each section are suitably connected, may be shipped flat with the walls folded down and when the purchaser desires to use the box, these walls are set up, the box then filled, and the two sections brought into interfitting relationship as shown in Figures 2 and 3. It will be observed that the end walls 22 and 23 embrace the end walls 18 and 19 and that these end walls are thus reinforced and prevented against displacement outwardly when the box is closed. The inner edges 37 and 38 of the walls 18 and 19 engage in the corners formed by the end walls 22 and 23 and their respective connecting members 39 and 40, the contents of the box preventing inward displacement of the end walls 18 and 19 and thereby rendering it difficult, without tearing the box, to reach into the box and remove its contents. The members 39 and 40 function themselves as gussets as do the members 27 and 27^a and 28 and 28^a. In constructing the box of my invention, the portions 39 and 40, as will best be seen in Figure 2, project into the box. In the box actually constructed, there is a double thickness, therefore, between the rear wall, that is, the common hinge wall 24, and the inner edge of the end wall 18, so that when the box is completely full and closed, the abutment of the gusset members 39 against the inner edge of the wall 18 cooperating with the contents of the box prevent the wall 18 being forced in.

wardly without being torn if an attempt is made to reach into the box and remove its contents. It will be obvious that the box is tied or otherwise held closed in shipment, and an attempt to reach up under the end 22 and remove the contents would result either in tearing the wall 22 away from the gusset 39 or in mutilating the wall 18.

In the actual manufacture of the box of the present invention, I find that in a standard box commonly employed in the market, on lots of 50,000, a material saving of material is effected, and in some instances the saving in material is equivalent, in round figures, to approximately 1,500 complete boxes and that less creasing and cut rule and wood stock is necessary in the die-work. In some instances as much as 100 pounds of flat wire for stapling may be saved. These figures are based on material required in similar boxes now on the market.

Having thus described my invention and illustrated its use, what I claim as new and desire to secure by Letters Patent is:

25 1. A receptacle including a pair of sections having complementary outer side and end walls, a portion between the sections forming a common side wall therefor, means for connecting the end walls of one of the sections 30 to said common side wall including diagonally folded flaps, said connecting means lying adjacent to said common side wall and

forming a retaining abutment engaging the end walls of the opposite section and preventing their inward movement, means for 35 fixedly securing one of the portions of each of said flaps to said common side wall to cause said flaps to move inwardly of the receptacle when the sections thereof are brought together, and a reinforcing member 40 lying against said common side wall and having notched ends forming reduced tongues extending beneath and being retained by the fixedly secured portions of said flaps.

2. A collapsible box section including a 45 main wall, walls angularly related thereto and forming the sides and ends of the section, adjacent side and end walls being connected by diagonally folded connecting gussets having one each of their portions thus 50 formed lying against and secured to the adjacent side wall, and a reinforcing member lying against said side wall and having reduced ends which underlie the folded gussets, and said reinforcing member being so 55 positioned that one margin thereof is adapted to engage said main wall whereby the latter cooperates with said folded connecting members to retain said reinforcing member against both lateral and longitudinal displacement.

In testimony whereof I have hereunto signed my name.

ALBERT J. VANCE.
